DESIGN.

M. BACHMANN.

BUST.

No. 18,855.

Patented Jan. 15,

UNITED STATES PATENT OFFICE.

MAXIMILIAN BACHMANN, OF PHILADELPHIA, PENNSYLVANIA, ASSIGNOR TO HARPER FORREST SMITH, SR., OF SAME PLACE.

DESIGN FOR A BUST.

SPECIFICATION forming part of Design No. 18,855, dated January 15, 1889.

Application filed October 4, 1888. Serial No. 287,240. Term of patent 7 years.

To all whom it may concern:

Be it known that I, MAXIMILIAN BACHMANN, a citizen of Berlin, and a subject of the Emperor of Germany, but now residing in the city and county of Philadelphia, State of Pennsylvania, have invented and produced a new and original Design for a Bust, of which the following is a specification, reference being had to the accompanying photograph, forming part thereof.

The bust is of a Templar. The face has a stern expression and is beardless. On his head is a helmet the rim of which is chased, and the front is decorated with an ornament, in the center of which is a St. Andrews cross. From the helmet hangs the representation of a piece of chain armor, completely covering the head all around, except the face. On his breast, fitting close and covering his chest and throat, is the representation of another piece of chain armor, over which is a close-fitting garment decorated in the center by a Maltese cross. Over all is thrown his mantle, fastened near the left shoulder by an ornament and decorated by a Maltese cross on his right shoulder. The back view shows only the helmet and chain armor, over which is thrown loosely his mantle. The base is simply a square base with the word "Templar" on the front of it.

What I claim as my invention, and desire to protect by Letters Patent, is—

The design for the bust of a Templar, having the shape, ornamentation, and characteristic features herein shown and described.

MAXIMILIAN BACHMANN.
